JEWELRY FINDING

Arthur C. Burnett, Newburgh, N. Y., assignor to
the City of Newburgh, N. Y., a municipal cor-
poration of New York

Application April 25, 1950, Serial No. 9,473

Term of patent 14 years

(Cl. D45—1)

To all whom it may concern:

Be it known that I, Arthur C. Burnett, a citizen of the United States, residing at Newburgh, State of New York, have invented a new, original and ornamental Design for a Jewelry Finding, of which the following is a specification, reference being had to the accompanying drawing, forming a part hereof.

Figure 1 is a plan view of a jewelry finding, showing my new design.

Figure 2 is a side elevation view thereof.

I claim:

The ornamental design for a jewelry finding, substantially as shown and described.

ARTHUR C. BURNETT.
